UNITED STATES PATENT OFFICE

114,453

DESIGN FOR A SAFETY REFLECTOR FOR AN AUTOMOBILE OR THE LIKE

Masick C. Magarian, Fresno, Calif.

Application April 16, 1938, Serial No. 76,571

Term of patent 3½ years

To all whom it may concern:

Be it known that I, Masick C. Magarian, a citizen of the United States of America, residing in Fresno, county of Fresno, and State of California, have invented a new, original, and ornamental Design for a Safety Reflector for an Automobile or the like, of which the following is a specification, reference being had to the accompanying drawing, forming part thereof, in which:

Figure 3 a rear elevation of my safety reflector; and

I claim:

The ornamental design for a safety reflector for an automobile or the like, substantially as shown,

MASICK C. MAGARIAN.
